UNITED STATES PATENT OFFICE.

FERDINAND ROCHOW, OF BROOKLYN, ASSIGNOR TO HIMSELF AND FRANZ OTTO MATTHIESSEN, OF NEW YORK, N. Y.

IMPROVEMENT IN ELEVATORS.

Specification forming part of Letters Patent No. 174,642, dated March 14, 1876; application filed September 23, 1875.

To all whom it may concern:

Be it known that I, FERDINAND ROCHOW, of Brooklyn, in the county of Kings and State of New York, have invented a new and Improved Hoisting and Lowering Apparatus, of which the following is a specification:

Figures 1, 2, and 3 represent face views of my improved hoisting and lowering mechanism, showing the dummy in different positions. Fig. 4 is a detail side view of the dummy.

Similar letters of reference indicate corresponding parts in all the figures.

This invention has for its object to provide a double hoisting and lowering apparatus with adjusting mechanism, whereby the hoisting and lowering process may be carried on between any two floors of a building. In warehouses such apparatus is mostly used; and it consists, usually, of two dummies or cages, that are suspended from the ends of a rope that passes over a drum in the upper part of the building, the length of rope being such that when the platform of one of the cages or dummies is level with the uppermost floor that of the other will be on a level with the lowermost floor. Now, it is frequently necessary or desirable to discharge goods from the uppermost floor to another than the lowermost floor of the building, or from an intermediate floor to one still farther below—in fact, to communicate between any two floors, not necessarily the uppermost and lowermost; and in this case the old arrangement of balanced lowering and hoisting apparatus will not answer, because the rope has a certain extent, whereby when one of the dummies is in line with a certain floor the other would not necessarily be in line with the other floor, with which it is desired the first cage shall communicate.

For rendering the apparatus adjustable, to enable any two floors to be connected, I combine, with one or both of the cages or dummies, a drum, which is hung in the same, and upon which the end of the hoisting or lowering rope is wound, so that, by turning such drum on the dummy, the length of the rope may be varied, and the desired object, consequently, attained.

In the drawing, the letters A, B, and C represent three floors of a structure in which my apparatus is put up, said apparatus consisting of two dummies or cages, D and E, which are connected by a rope, F, that passes over a drum, G, hung above the top floor A, as shown. The drum G is applied with suitable brake and other devices that are usually employed on such apparatus. One end of the rope F is fastened to, and in part wound upon, a drum, H, that is hung in the upper part of the cage or dummy E, said drum H being provided with a suitable ratchet-wheel, a, and click, which will prevent the unwinding of the rope from said drum, except when the click is thrown out of contact with the ratchet-wheel. The other end of the rope F is either fastened to the cage D, in the usual manner, or to a drum hung in the cage D, the same as the drum H is on the cage E.

In Fig. 1 the apparatus is shown to connect the upper floor A with the lower floor C—that is, the length of rope is such that when the platform of one cage, D, is in line with the upper floor A that of the other cage, E, will be in line with the bottom floor C, and vice versa—so that when a load is put on the top dummy, and the same thereupon lowered to a level with the floor C, the other dummy will thereby be raised to a level with the floor A.

In Fig. 2 the same apparatus is shown as connecting the floors B and C—that is, the rope F, by being partly unwound from the drum H, is lengthened sufficiently to allow one cage to be in line with the floor B when the other is in line with C.

In Fig. 3 the same apparatus is shown with the rope F considerably shortened by winding it upon the drum H, so that the two cages will connect the floors A and B. Thus, by the application of the drum H to one or both of the cages, I am enabled to connect any two floors of the structure, no matter how many floors there may be in the building, and to thus obtain an adjustable hoisting and lowering mechanism much more useful than those heretofore employed. The apparatus may, by the use of the drum H, be adjusted while it is in operation.

The invention is shown applied to apparatus

in which there are two dummies, but may, with equal effect, be applied to apparatus having but one dummy, which is counterbalanced by a weight at the other end of the rope, and to other equivalent apparatus; and, in place of the ratchet-wheel and click *a* on the drum *H*, other means for locking said drum may be employed.

I claim as my invention—

1. The dummy *E* of a hoisting and lowering apparatus, combined with the winding-drum *H*, which is hung in said dummy, and to which one end of the hoisting-rope is secured to be wound upon said drum, to be lengthened or

shortened, substantially as and for the purpose herein shown and described.

2. The combination of the two dummies *D* *E* with the hoisting-rope *F*, that connects them, and with the drum *H*, which is hung in the dummy *E*, for the purpose of adjusting the length of the rope *F*, substantially as herein shown and described.

The foregoing description of my invention signed by me this 6th day of September, 1875.

F. ROCHOW.
